UNITED STATES PATENT OFFICE.

VICTOR WILLOUGHBY, OF RIDGEWOOD, NEW JERSEY, ASSIGNOR TO AMERICAN CAR AND FOUNDRY COMPANY, OF NEW YORK, N. Y., A CORPORATION OF NEW JERSEY.

MINE CAR.

Application filed June 15, 1925. Serial No. 37,250.

- In the drawings:
- Fig. 1 is a side elevation of a mine car constructed in accordance with this invention, parts being broken away to show other parts more clearly;
- Fig. 2 is a top plan view of the mine car shown in Fig. 1; and
- Fig. 3 is a partial vertical transverse section of the mine car shown in Fig. 1 taken 10 on the line 3—3 of Fig. 2.
- This invention relates to composite mine cars and has as an object to provide an improved mine car of the type specified having a wood center floor portion and wood 15 sides, metal side floor portions and metal reinforcing at the junction of the side floor portions and the wood sides. It is also an object of this invention to provide flanged sills formed integral with the side floor portions and journal boxes shaped to fit the 20 sills and which will reinforce the sills, directly support the sill flanges and aid in supporting the side floor portions.
- With these and other objects in view a 25 mine car constructed in accordance with this invention comprises, as shown in the drawings, metal plates 1 forming the side floor portions of the car and having their inner edges bent to form flanged sills 2 with downwardly projecting vertical webs 3 and inwardly projecting bottom flanges 4. The outer edges of the plates 1 are bent to lie in a plane parallel with and slightly above the plane of the body of the plates 30 and are reinforced by angles 5 having inwardly projecting flanges 6 riveted to the plates 1 and upwardly projecting flanges 7. To the sills 2 are secured journal boxes 10 formed with Z-shape portions which fit the 35 sills 2 and flanges 11 secured to the bottom flanges 4 of the sills 2 by bolts 12 and flanges 13 secured by bolts 14 to the plates 1 so that the sill flanges and side floor portions are directly supported on the journal boxes. Mounted in the journal boxes 10 are 45 axles 15 having wheels 16 secured thereon, the top portions of the wheels being accommodated in openings 17 formed in the plates 1 and covered by flanged curved wheel hoods 18 which extend at uniform 50 height to the outer edges of the plates 1 and have their outer edges reinforced by the angles 5 which are bent to conform to the shape of the outer edges of the wheel hoods 18. Thus the reinforcement of the outer 55 wheel hood edges and of the side floor plates 1 is continuous at the junctions of the hoods 18 with said plates 1, where it is particularly needed, and is independent of the car sides. The wheel hoods 18 have their 60 flanges secured by rivets 19 to the plates and by bolts 14 to the plates 1 and the flanges 13 of the journal boxes 10.
- At the outer edges of the side floor portions are mounted longitudinally extending 65 planks forming wood sides 20 which have their lower edges gained to receive the vertical flanges 7 of the angles 5, the lowermost planks being cut away to conform to the shape of the wheel hoods 18. The sides 70 20 are supported at regular intervals from end to end of the car by braces 21 secured to the sides by bolts 22. The braces 21 extend from side to side of the car, being secured to the angles 5 and side floor portions 75 by rivets 23 and bent downwardly to pass beneath the bottom flange 4 of the sills 2 to which they are secured by the bolts 12.
- Extending longitudinally of the car is the inverted U-shape drawbar or buffer 80 beam 25 having laterally projecting flanges 26 secured to the braces 21 by rivets 27. Between the buffer beam 25 and the sills 2 are the planks 28 having edges gained to fit the beam and sill flanges. The beams 25 are secured to the braces 21 by bolts 29 and with the web 30 of the buffer beam 25 form the center floor portion of the car. Extending between the plates 1 are ties 31 which 85 rest upon the planks 28 and buffer beam 25 and are secured to the planks by the bolts 29 and to the plates 1 by rivets 32.
- The buffer beam 25 and adjacent planks 28 project at the car ends and are provided with bumpers 34 comprising top plates 35 and bottom plates 36 spaced therefrom and joined thereto by curved end plates 37, the top plates 35 and bottom plates 36 covering the projecting ends of the planks 28 and buffer beam 25 and extending inwardly as 90 far as the inner edges of the end braces 21. The bottom plates 36 are spaced from the bottoms of the planks 28 and buffer beam 25 providing openings for filler blocks 38 which are gained out to receive the angles 39 and end braces 21 which tie the planks 28 and buffer beam 25 together. To the 95 buffer beams 25 are secured coupling mem-

bers 40 having their outer ends spaced from the top plates 35 of the bumpers 34 to provide openings to receive the usual coupling links, the coupling members 40 and bumpers 34 being provided with aligned openings to receive the usual coupling pins 41.

The car body is closed at one end by a swinging end gate 43 carried by arms 44 pivotally mounted at 45 on the sides 20 of 10 the car while the other end of the car is closed by a fixed end 46 secured to the car sides and floor. Mounted in brackets 50 secured to the flanges 4 of the sill 2 is a shaft 51 having crank arms 52 pivotally connected 15 to ends of flexible brake bands 54 which have their other ends connected to brackets 55 secured to the adjacent braces 21 and plates 1. At one end the shaft 51 is provided with a crank arm 56 pivotally connected to 20 one end of a link 57 the other end of which is pivotally connected to a brake operating lever 58 pivotally mounted at 59 in a bracket 60 carried by the adjacent plate 1. The brake lever 58 projects upwardly through 25 an opening in the plate 1 and has its upper end bent outwardly to provide a handle 61 which projects over the car side, the car lever. A plate 62 connected by flanges 63, 64 and 65 to the plate 1, the car side 20 and the 30 fixed end 46 forms with the plate 1, side 20 and end 46 a pocket in which the brake lever operates. To the car side 20 is secured an angle 70 having teeth adapted to be engaged by a lug 71 on the brake lever 58 to hold the 35 brake lever in brake applied position.

It will be noted that the central portion of the floor is supported upon the lower flanges 11 of the journal boxes and between the upper portions of such journal boxes, to the upper flanges 13 of which the side floor portions 1 are connected. The journal boxes, it will be noted, have supporting flanges or faces in different planes.

What is claimed is:

- 45 1. In a mine car, metal side floor portions having their inner edges bent to form flanged sills, wheel housings secured to said floor portions and journal boxes secured to the flanges of said sills.
- 50 2. In a mine car, side floor portions having sills formed integral therewith, wheel housings secured to said floor portions and journal boxes fitting said sills.
- 55 3. In a mine car, side floor portions having sills formed integral therewith, separately formed wheel housings secured thereto and journal boxes supporting said sills.
- 60 4. In a mine car, metal side floor portions having their inner edges bent to form flanged sills and journal boxes having Z-shape portions fitting said sills and secured to said sill flanges.
- 65 5. In a mine car, metal side floor portions having their inner edges bent to form flanged sills and journal boxes secured to

said sills and having Z-shape portions fitting said sills.

6. In a mine car, metal side floor portions having their inner edges bent to form flanged sills, flanged journal boxes having Z-shape portions fitting said sills and means securing said journal box flanges to the flanges of said sills.

7. In a mine car, metal side floor portions having their inner edges bent to form flanged sills having vertical webs and journal boxes having flanges on different levels secured to said sills and side floor portions.

8. In a mine car, metal side floor portions having their inner edges bent to form flanged sills having vertical webs and journal boxes having angular portions fitting said sills and flanges on different levels secured to said sills and side floor portions.

9. In a mine car, metal side floor portions having their inner edges bent to form flanged sills, said side floor portions having wheel openings formed therein and extending to the outer edges of said side floor portions, wheel hoods closing said openings and secured to said sills and angles reinforcing the outer edges of said side floor portions and wheel hoods.

10. In a mine car, metal side floor portions having wheel openings therein extending to the outer edges thereof, wheel hoods covering said openings and extending to the outer edges thereof and continuous longitudinally extending means reinforcing the outer edges of said side floor portions and wheel hoods, independently of the car sides.

11. In a mine car, side floor portions having wheel openings therein extending to the outer edges thereof, wheel hoods covering said openings, angles reinforcing the outer edges of said floor portions and wheel hoods and sides carried by said side floor portions, said sides being cut away to receive said wheel hoods.

12. In a mine car, side floor portions, having sills formed integral therewith, said side floor portions having wheel openings therein extending to the outer edges thereof, wheel hoods covering said openings and secured to said sills and angles reinforcing the outer edges of said floor portions and wheel hoods.

13. In a mine car, metal side floor portions having their inner edges bent to form flanged sills, sides carried by said side floor portions, angles reinforcing the outer edges of said side floor portions and braces connecting said sides, angles, side floor portions and sill bottom flanges.

14. In a mine car, metal side floor portions having their inner edges bent to form flanged sills, journal boxes supporting said sill flanges and bracing means for said side floor portions secured to said sill flanges.

15. In a mine car, metal side floor por-

- tions having flanged sills formed integral therewith, journal boxes having flanges on different levels supporting said sill and side floor portions and bracing means for said side floor portions secured to said sills.
16. In a mine car, metal side floor portions having their inner edges bent to form flanged sills having vertical webs, journal boxes having flanges on different levels secured to said sills and side floor portions and bracing means for said side floor portions secured to said sill flanges.
17. In a mine car, metal side floor portions having their inner edges bent to form flanged sills having vertical webs, journal boxes having flanges supporting said sills and bracing means for said side floor portions connecting said sill flanges.
18. In a mine car, metal side floor portions having their inner edges bent to form flanged sills, angles reinforcing the outer edges of said side floor portions, journal boxes having flanges supporting said sill flanges and bracing means for said side floor portions connecting said sills and angles.
19. In a mine car, metal side floor portions having their inner edges bent to form sills, angles reinforcing the outer edges of said side floor portions, journal boxes having flanges on different levels supporting said sills and side floor portions and bracing means for said side floor portions connecting said sills and angles.
20. In a mine car, a plurality of journal boxes in combination with supporting sills and side floor portions both supported directly on said boxes.
21. In a mine car, a plurality of journal boxes having supporting faces in different planes in combination with supporting sills and side floor portions supported thereon.
22. In a mine car, a plurality of journal boxes each having a plurality of relatively flat faces in different planes in combination with sills and floor portions connected with said flat faces.
23. In a mine car, a combined side floor portion and supporting sill in combination with a journal box directly connected to the sill and to the side floor.
24. In a mine car, a plurality of journal boxes having supporting faces in different planes, a wood floor supported above the lower plane and a metal side floor connected with said journal boxes in a higher plane.
25. In a mine car, journal boxes each having supporting faces in different planes, a central floor portion carried above the plane of the lower supporting faces and side supporting portions supported on the higher supporting faces.
26. In a mine car, journal boxes each having supporting faces in different planes, a central floor portion carried above the plane of the lower supporting faces and side supporting portions supported on the said lower supporting faces and also on the higher supporting faces.
27. In a mine car, a plurality of journal boxes, a central floor supported intermediate certain portions of said journal boxes and side floor portions supported upon and secured to portions of the journal boxes beyond said central floor.
28. In a mine car, journal boxes each having supporting faces in different planes, a central floor portion intermediate said planes, side floor portions extending outwardly from said central floor portion and supported at a plane relatively higher than the plane of the support for the central floor portion.
29. In a mine car, a horizontal metal side floor portion having its inner edge bent to form a flanged sill and journal boxes secured to both flanges of said sill.
30. In a mine car, horizontal metal side floor portions having wheel openings therein, wheel housings secured to said floor portions and closing said openings, said side floor portions having their inner edges bent to form flanged sills and journal boxes secured to the flanges of said sills.
31. In a mine car, metal side floors having wheel openings therein, wheel housings secured to said floors and closing said openings, said side floors having their inner edges bent to form sills and journal boxes secured to said sills and side floors.
32. In a mine car, a metal side floor portion having its inner edge bent to form a sill and a journal box having flanges at different levels secured to said sill and side floor portion.
33. In a mine car, a metal side floor portion having its inner edge bent to form a sill and a journal box secured to said sill and said side floor portion.

In witness whereof I have hereunto set my hand.

118

VICTOR WILLOUGHBY.
